TYPEWRITING AND LIKE MACHINE

Elbert S. Dodge, Ilion, and Wilfred L. Philbin,
Frankfort, N. Y., assignors to Remington Rand
Inc., Buffalo, N. Y., a corporation of Delaware

Application August 11, 1934, Serial No. 739,384

51 Claims. (Cl. 197—176)

Our invention relates to typewriting and like machines and more particularly to tabulator mechanism and features associated therewith.

One of the main objects of our invention, generally stated, is to provide efficient automatically operating, power-actuated, tabulator mechanism.

Another object of the invention is to provide efficient means for automatically locking printing keys against actuation when the automatic tabulator mechanism is in use.

A further object of the invention is to provide simple and effective means that may be set at will to render the automatic, power actuated, tabulator mechanism inoperative.

Another object of the invention is to provide a column jumping mechanism and means for automatically rendering the automatically operating tabulator mechanism ineffective when said column jumping mechanism is actuated.

A further object of the invention is to provide denominational selecting tabulator mechanism that may be operated without being interfered with by the automatically operating tabulator mechanism.

A further object of the invention is to provide means for automatically rendering the automatically operating tabulator mechanism ineffective when the carriage is released with the aid of one of the usual carriage release keys.

A still further object of the invention is to render the automatically operating tabulator mechanism inoperative when the carriage is being returned by its power actuated carriage return mechanism.

Another object of the invention is to provide mechanism of the character indicated above which may be incorporated in a machine having two relatively movable frame sections and which will not interfere with such relative movement of the sections and which is so constructed that cooperative parts of the mechanism will be brought into cooperative relation when the frame sections are brought together.

Another object of the invention is to so construct the foregoing features that they may be readily embodied in machines now on the market without materially modifying the existent structural features of such machines.

To the above and other ends which will hereinafter appear, our invention consists in the features of construction, arrangements of parts and combinations of devices set forth in the following description and particularly pointed out in the appended claims.

In the accompanying drawings wherein like ref-

erence characters represent corresponding parts in the different views—

Fig. 1 is a fragmentary, vertical, fore and aft sectional view of a portion of the machine showing features of the present invention embodied therein, the view showing the parts in normal position. 5

Fig. 2 is a like view of the same with parts omitted and showing the automatically operating tabulator mechanism as it appears in the 10 actuated position.

Fig. 3 is a skeletonized, detail perspective view showing the automatically operating control mechanism for the tabulator and key lock.

Fig. 4 is a detail, fragmentary front view of a 15 portion of the means for rendering the automatically operating tabulator mechanism and key lock controlled therefrom inoperative.

Fig. 5 is a detail perspective view of a portion of the power actuated means for operating the 20 tabulator mechanism.

Fig. 6 is an enlarged, detail, vertical transverse sectional view showing some of the parts disclosed in Fig. 5; the section being taken on the line 6—6 of Fig. 1 and looking in the direction of the arrows 25 at said line.

Fig. 7 is an enlarged, detail, fragmentary, perspective view with parts in section of one form of key locking means and some of the associated parts. 30

Fig. 8 shows in perspective several controlling cams of different lengths for controlling the operation of the automatic tabulator and key lock.

Fig. 9 is a detail, bottom plan view of one of said controlling cams shown attached to its supporting 35 bar.

Fig. 10 is a detail, fragmentary, perspective view of the supporting bar on which the controlling cams are mounted.

Fig. 11 is a fragmentary, diagrammatic side view showing portions of the two frame sections and some of the parts carried thereby. 40

Fig. 12 is an enlarged, detail, side view of the actuating cam for the automatic tabulator mechanism and some of the associated parts. 45

Fig. 13 is a detail, fragmentary, side view with parts in section showing a different form of key locking means from that represented in Fig. 7.

Fig. 14 is a detail, fragmentary, perspective view 50 of part of the mechanism.

Fig. 15 is a detail, fragmentary side view of parts of the structure shown in Fig. 14.

Fig. 16 is a detail, fragmentary, perspective view 55 of a part of the automatic tabulator mechanism.

and some of the associated parts, with the parts shown in normal position.

Fig. 17 is a front view of a portion of the same showing some of the parts in the actuated position.

Fig. 18 is an enlarged, detail, fragmentary, top plan view of a portion of the structure shown in Fig. 16 and with parts in section.

Fig. 19 is a detail, fragmentary, top plan view showing the tabulator keys.

Fig. 20 is a skeletonized side elevation with parts in section of the column jumping mechanism, showing the parts in actuated position.

Fig. 21 is a like view of a portion of the same, showing the parts in normal position.

The invention is shown embodied in the present instance in a Remington electrified bookkeeping machine in which the various features of the invention may be readily incorporated without materially modifying existing structural features of said machine. It should be understood, however, that the invention is not restricted to its embodiment in such machine but may be employed in typewriting and like machines generally, wherever found available. It will be understood that the Remington electrified bookkeeping machine includes computing mechanism, but for the purpose of the present invention it is unnecessary to illustrate such computing mechanism.

In the accompanying drawings only so much of the Remington electrified bookkeeping machine is disclosed as is necessary to arrive at an understanding of the present invention in its embodiment therein.

Referring more particularly to Figs. 1 and 11 it will be seen that the machine frame comprises a lower section 15 and an upper section 16 hinged together at the rear of the machine as indicated at 11. This is to afford a relative movement between the sections, as indicated in dotted lines in Fig. 11, in order to give ready access to parts contained within the frame. Some of such parts are carried by the upper frame section and others are carried by the lower frame section. Some of such parts in the two frame sections coact with each other and they are brought into cooperative relation when the frame sections are brought together, as indicated in Fig. 11. This applies to some of the parts of the present invention as well as other parts, as will hereinafter appear.

The usual carriage 18 (Fig. 1) which carries a platen 19 is carried by the upper frame section 16 and is supported on roller bearings to travel from side-to-side of the machine over the top plate 20. The bearing rollers at the rear of the carriage are shown at 21. The carriage is advanced by the usual spring drum (not shown) under control of its escapement mechanism. The escapement mechanism includes a feed rack 22 carried by arms 23 which are pivoted at 24 to the rear cross bar 25 of the carriage. This rack meshes with a feed pinion 26 operatively connected in the usual manner with an escapement wheel, not shown. When the feed rack is lifted and disengaged from its pinion 26 the carriage is free to travel in the direction of its feed. At a tabulating operation that is what takes place, the carriage moving until it is arrested by coacting tabulator stops as will presently appear.

In the present machine various parts are driven from a continuously operating electric motor, the shaft 27 of which is shown in Fig. 11. Said shaft carries a driving pulley 28 with the usual belt, pulley and geared connections therefrom to various parts of the machine including a continuous-

ly rotating shaft 29, as disclosed for example in the application of Frederick A. Hart Serial No. 634,670. This shaft 29 is operative for other purposes in said Remington machine but in the present machine we utilize it for the purposes of our present invention.

Referring more specifically to Figs. 1, 2, 5, 6 and 12 of the drawings, it will be seen that the driving shaft 29 which is supported in bearings in the side plates of the lower or base frame section 15, has a cam 30 loosely mounted thereon near the left-hand end of said shaft. To the right of this cam and adjacent thereto is a locking wheel 31 fixed on the shaft 29 to turn therewith. The periphery of the locking wheel is provided with teeth 32 and interdental spaces 33. A locking pawl 34 is pivoted at 35 on the right-hand side of the cam 30 and the engaging end of the locking pawl is adapted to enter any of the interdental spaces 33 and thus lock the cam to turn with the continuously 10 rotating shaft 29. A rod 36 (Fig. 12) is pivoted to one end of the pawl 34 and extends at its free end through an opening in a bracket arm 37 secured to the cam 30. An expansion spring 38 surrounds the rod 36 and bears at one end against the bracket 15 arm 37 and bears at its other end against a shoulder on the rod 36. The force of the spring 38 is thus exerted to move the engaging end of the locking pawl 34 into an interdental space 33 in the locking wheel and connect the cam 30 to turn 20 with the continuously rotating driving shaft 29.

The pawl 34 is normally maintained disconnected from the locking wheel by a trip arm 39 which engages a projection 40 on the pawl 34, thus holding the pawl against the force of its 25 spring 38, as shown in Fig. 12.

A second trip arm 41 is formed integral with the arm 39 so that the connected arms 39 and 41 constitute a bell crank lever pivoted at 42 and spring pressed to the normal Fig. 12 position by a contractile spring 43. It will be understood that when the double trip 39, 41 is moved from the Fig. 1 to the Fig. 2 position the cam 30 is connected to turn with the driving shaft 29 for approximately one quarter of a 40 revolution when the cam is disengaged from the shaft by the interposed trip arm 41 coacting with the pawl 34 and disengaging it from the locking wheel 31. This movement of the cam 45 30 is effective to project a tabulator stop, release the carriage from control of its escapement mechanism and to actuate the key locking means, as will hereinafter appear.

In order to prevent the reaction of the pawl 55 spring 38 from turning the loosely mounted cam 30 backward from its normal position shown in Fig. 12 and from its actuated position shown in Fig. 2, there is provided special means which will now be described.

A second cam 44 is fixedly connected to and maintained spaced apart from the cam 30 by shouldered rivets 35 and 45, the rivet 35 constituting the pivot for the pawl 34. Two high spots 46 and 47 are provided on the cam 44. In the normal position of the parts shown in Fig. 12 a spring pressed detent roller 48 coacts with the high spot 46 and overcomes the tendency of the cam 30 to turn backward under the reaction of its pawl spring 38. In a like manner 60 said roller detent coacts with the high spot 47 on the cam 44 when the parts are in the actuated position shown in Fig. 2. The detent roller 48 is carried at one end of an angular lever 49 pivoted at 50 and connected to a con- 65 70 75

tractile spring 51 by which the detent roller is pressed against the cam 44.

The parts which are actuated by cam 30 are constructed as follows.

5 A roller 52 bears against the periphery of the cam 30 and is carried by an upright arm 53 pivoted at its lower end at 54. The upper end of the arm 53 is pivoted at 55 to a rearwardly extending link 56. Said link is bifurcated at its 10 rear end as indicated at 57, to straddle a headed pin 58 which projects laterally from an upright arm 59. This arm is pivoted at its lower end on a pivot rod 60 and has a rearwardly extending arm 61 to which a contractile spring 62 is connected, the upper end of said spring being anchored on a rod 63. The upper end of the arm 59 is fixedly connected by a cross rod 64 (see Figs. 5 and 6) to an arm 65 which is likewise pivoted on the pivot rod 60 and has an upwardly and rearwardly extending end 66 that is in register with a horizontally movable actuating slide 67. This slide is slotted at 68 to receive parallel rods 69 on which the slide is supported for movement fore and aft of the machine in a 15 guide frame 70 having front and rear guide combs 71 and 72 in guide slots in which the slide 67 is received. The frame 70 and the rods 69 are connected with and supported by two arms 73 pivoted at 74 to the sides of a tabulator 20 frame 75 that is connected to the upper frame section 16. A contractile spring 76 is connected at one end to an arm 73 and is anchored at the other end to a pin 77 on the tabulator frame. One of these springs may be connected to each 25 arm 73 and the force thereof is exerted to normally maintain an extension 78 on the associated arm in contact with the companion pin 77 which constitutes a stop therefor.

It should be understood that the arm 65, 40 except as hereinbefore indicated, is similar to the remainder of a series of such arms 65^a, each of which coacts with a slide 67^a that corresponds to the slide 67. However, the right-hand arm 65^b while constructed like the arms 65^a operates for a somewhat different purpose as will hereinafter appear.

It will be understood from this construction that if the actuating arm 65 or any corresponding arms 65^a or 65^b should happen to be in the 45 actuated position when the upper frame section 16 is moved down into contact with the lower frame section the corresponding slide 67 or 67^a will contact with such actuated arm and hold the frame 70 against the force of the springs 76, thereby changing the normal relation of said frame, and the parts carried thereby, to the frame section 16. As soon, however, as the 50 actuated arm 65, 65^a or 65^b is withdrawn and returned to normal position, the springs 76 will cause the frame 70 and the parts carried thereby to be lowered and assume their normal relation to the upper frame section 16 and bring the slide 67 or 67^a into cooperative relation with its actuating arm 65, 65^a or 65^b and no injury 55 to the parts will result.

The rear end of the slide 67 is, under normal conditions, in cooperative relation with the lower end of a tabulator stop actuating lever 79 which is, or may be, one of a series of such levers 60 usually employed, say, that one at the left-hand of the series which ordinarily actuates the lowest denominational stop. This lever is pivoted intermediate its ends as indicated at 80 (Fig. 1), in the tabulator frame 75 and is returned to its 65 normal position by the usual spring 81 asso-

ciated therewith. The upper end of this lever is received in a notch 82 in a tabulator stop 83 mounted in the usual manner to slide fore and aft of the machine in the tabulator frame.

The remainder of the arms 65^a, their companion slides 67^a, stop levers 79 and stops 83 may be actuated by any suitable means, such for example as by the power actuated means disclosed in the previously mentioned application of Frederick A. Hart, Serial No. 634,670. 10

When the tabulator stop 83 controlled by the cam 30 is projected to effective position, as shown in Fig. 2, it is interjected in the path of the next oncoming column stop 84. The column stops are adjustable to different positions along a column stop bar 85 in the usual manner to determine the columnar positions of arrest of the carriage. The column stop bar is connected near its ends to bracket arms 86 secured at their forward ends to the back rail or cross bar 25 of the 20 carriage.

The means by which the power driven cam 30 is controlled and by which the carriage is released from control of its escapement mechanism will now be described.

Secured to and beneath the column stop bar 85 is a channel bar 87 that preferably extends substantially throughout the length of the column stop bar. As shown in Fig. 10 this channel bar 87 is secured to the column stop bar 85 by 30 headed clamping screws 88 and has a limited lengthwise adjustment on said stop bar due to the elongated slots 88^a through which the stems of the screws 88 pass. The channel bar is tapped transversely at 89 at letter space intervals substantially throughout the length thereof for attachment at different points in its length of one or more controlling cams or contact blocks or devices 90, shown in detail in Figs. 8 and 9. The bar 87 has a longitudinally extending groove 40 or recess 91 in the under side thereof which extends substantially throughout the length of the bar. Each block 90 has a projection 92 on the upper side thereof which is adapted to be seated in the groove 91 when mounted in place 45 on the bar 87. Each block 90 also has one or more transverse openings 93 therethrough for the passage of the stems of headed screws 94 (see Figs. 3 and 9) which are received in certain of the tapped openings 89 depending on 50 the position where each block 90 is to be located along the bar 87. Each opening 93 is countersunk at the lower face of the block, as indicated at 95 in Fig. 9, to receive the head of the companion screw 94. The advancing end of each 55 block 90 has a transverse bevel or cam face 96 thereon that terminates at its high point in a dwell 97 formed by the entire rear side of the block, for purposes which will hereinafter appear. It will be understood from what has been 60 pointed out that the length of each block 90 determines the length of the dwell thereon. The opposite end of each cam block has a second cam face 96^a thereon that extends at right angles to the cam face 96 on the other end of the block, 65 and the purpose of which will hereinafter appear.

The function of these cam blocks 90 will best be understood by a consideration of Fig. 3 from which it will be seen that a trip lever 98 has a 70 contact end 99 that normally extends into the path of the blocks 90, and when the cam face 96 on the front end of one of the blocks engages the end 99 of the lever the latter will be shifted bodily towards the rear of the machine. This 75

movement of the lever 98 is brought about due to the manner in which the lever is mounted, which will now be described.

The lever 98 is pivoted intermediate its ends 5 on a headed pivot 101 which is carried by a sheet metal frame designated as a whole by the reference numeral 102. This frame has depending ears 103 by which it is pivoted at 104 to a bracket 105 secured by screws 106 to the top 10 plate 20 of the machine. The left-hand end portion of the trip lever 98 has a depending portion 107 that is pressed down into contact with an arm 108 by a light spring 109. This spring is coiled about a screw stud 110 on the frame 15 102 and bears at one end against said frame and at the other end bears down against a stud 98^a carried by the lever 98. The right-hand end of the trip lever 98 coacts with an arm 111 which limits the counter-clockwise movement of the lever 98 on its pivot 101 under the action of the spring 109. Referring more particularly to Figs. 1 and 2 it will be seen that an adjustable screw stop 105^a is carried by an arm on the bracket 105 and coacts with the frame 102 to limit the 20 clockwise movement of the latter around its pivots 104 under the reactive force of a contractile returning spring 102^a.

The action of a cam 96 exerts a rearwardly directed force on the lever 98 and it, together 30 with the frame 102 on which it is mounted, is turned towards the rear of the machine around the pivots 104 and against the force of the returning spring 102^a. The result of this is to effect a downward movement of a rearwardly extending arm 112 fixed on the frame 102. This movement brings about a connection of the cam 35 30 to its continuously rotating driving shaft 29 and the associated tabulator stop 83 will be power driven to operative position as will now be described.

The rear end of the arm 112 has a contact shoe 113 that overlies the upper free end of a downwardly extending two-part rod 114. The lower end of this rod coacts with one arm 115 of a sheet metal releasing member pivotally supported on the pivot rod 60 and having a forwardly extending arm 116 that extends beneath an arm 117 of the trip 39, 41. It follows that when the rod 114 is depressed as described, the 50 trip 39, 41 will be turned against the force of its spring 43 to the Fig. 2 position. This results in releasing the trip arm 39 from the pawl 34 enabling the pawl to engage the locking wheel 41 and causing the cam 30 to turn with its shaft 55 29 to project the associated tabulator stop 83, as shown in Fig. 2. The release of the trip arm 29 resulted in interposing the other trip arm 41 in the path of the pawl 34 so that when the cam 30 reaches the Fig. 2 position the pawl 34 will 60 be automatically disengaged and the projected tabulator stop 83 will be held in its projected position.

The length of time that the projected stop 83 is held in such position is determined by the length 65 of the dwell 97 on the controlling cam 90 by which the automatic actuation of the stop is brought about. Thus, if a relatively long tabulating jump of the carriage is to be provided, then a proportionately long cam block 90 is provided. If a 70 relatively short tabulating jump of the carriage is to be provided, then a relatively short cam block 90 will be brought into action. In short, the length of time that the trip device 39, 41 is maintained in the actuated position shown in Fig. 2 is determined by the length of time that the lever

98 is on the dwell 97 of a controlling cam 90, and a cam block with the requisite length of dwell to accord with the extent of travel of the carriage is employed in each instance.

When a controlling cam block 90 has passed 5 the control lever 98, said lever, the frame 102 which carries it and the parts controlled thereby are returned by their respective returning springs to normal position shown in Fig. 1. This is brought about by the withdrawal of the trip arm 10 41 from engagement with the pawl 34, enabling it to reengage the locking wheel 31 and complete the cycle of the cam 30 where it is arrested by the trip arm 39 again engaging the pawl 34 and releasing it. 15

It will be understood, of course, that the set-up of the column stops 84 will accord with the set-up of the cams 90. In other words that each column stop 84 will be set to accord with the setting of the associated cam 90 so that after the 20 cam 30 has been connected to the shaft 29 and projects its stop 83 this condition will maintain as long as the control lever 98 rides on the dwell 97 of the active cam 90. Therefore the associated column stop 84 should be set so as to coact 25 with the cam controlled projected stop 83 at about the time the control lever 98 rides off the rear end of the dwell 97 of the active cam 90. Therefore, the carriage will be arrested by the stop 83 controlled by the cam 30 and the stop 84 30 associated with the active cam 90 before said stop 83 is withdrawn and also before the feed rack 22 is reengaged with its feed pinion during the completion of the cycling of the cam 30, as will presently appear. 35

In the return movement of the carriage to the right the cam faces 96^a on the blocks 90 will successively engage the controlling lever 98 and turn it around its pivot 101 against the force of the spring 109. At this time the frame 102 will not 40 be rocked on its pivots 104 and the automatic control of the tabulator will not be effected.

We prefer to employ an adjustable screw stop 111 (Figs. 1 and 2) carried by a fixed supporting plate *a* to coact with and limit the return movement of the arm 117 and the trip member of which it forms a part. 45

Of course it will be understood that when the tabulator stop 83 controlled by the cam 30 is automatically projected to effective position it is necessary to free the carriage from control of its escapement mechanism. The means by which this is effected will now be described. 50

From a consideration of Figs. 1 and 2 it will be seen that a universal bar 118 constitutes part of a frame 119 pivoted at 120 to the tabulator frame 75. This universal bar 118 extends back of the tabulator stop lever 79 and any other such levers that may be employed in the machine and is actuated by an operation of any of said levers. A 60 forwardly extending arm 121 on the pivoted frame 119 carries a headed pin 122, the stem of which passes through a longitudinally extending slot 123 in an upright link 124. The lower end of this link is pivoted at 125 to a crank arm 126 fixed 65 on a rock shaft 127. There is a second crank arm 128 on this shaft which is pivoted at 129 to an upwardly and rearwardly extending link 130, the upper end of which is pivoted at 131 to a carriage releasing device 132. This releasing device 70 132 is pivotally supported at 133 on a bracket secured to the top plate 20 of the machine and has a contact shoe 134 which underlies the feed rack 22. When, therefore, the tabulator stop 83 or any of the like stops is projected to operative 75

- position, shown in Fig. 2, the universal bar 118 will be actuated and rock the releasing device 132 through the intermediate connection to elevate the feed rack 22 and disengage it from the feed 5 pinion 26. This frees the carriage from control of its escapement mechanism and under the operation of the automatic tabulator mechanism the carriage will be maintained free until the active control cam block 90 passes the control 10 lever 98 and the carriage is arrested by the co-acting tabulator stops. After this the cam 30 completes its cycle and the parts are restored to the normal Fig. 1 position, the feed rack 22 re-engaging the feed pinion 26.
- 15 We have provided means whereby the automatically operating tabulator mechanism may at will be rendered inoperative and maintained inoperative as long as desired. This mechanism will now be described.
- 20 The arm 108 hereinbefore referred to (see Fig. 3) is in the nature of a crank arm fixed to and projecting forwardly from a rock shaft 135. This shaft turns in bearings in ears 136 which form parts of the bracket 105. The left-hand end of 25 the rock shaft 135 carries a crank arm 137 to which a depending link 138 is pivoted at 139. The lower end of this link is slotted at 140 to receive the stem of a headed pin 141 on a crank arm 142 fixed to a rock shaft 143.
- 30 The link 138 carries a laterally projecting stud 144 over which extends the rear end of a lever 145. Said lever is pivotally supported intermediate its ends, as indicated at 146, on a stud that projects from the top of the usual control 35 box 147 of the carriage return mechanism located at the left-hand side of the machine. The forward end portion of the lever 145 is guided in a slot 148 of a fixed guide plate 149 and is held in the lower end of said slot by a spring 150 when 40 the tabulator mechanism is functioning automatically. Should the operator desire to render the automatic tabulator mechanism inoperative it is merely necessary to lift the forward end of the lever 145 with the aid of the finger piece 151 and then deflect the lever to the right and seat it in the elevated locking notch 152 in the guide plate, as shown in dotted lines in Fig. 4. This 45 results in moving the link 138 downward thereby rocking the shaft 135 and elevating the arm 108. 50 As a consequence the control lever 98 will be rocked around its pivot 101 thus carrying the upper end 99 of said lever down out of the path of the cam blocks 90 and the automatic tabulator mechanism will thus be rendered and maintained 55 inoperative.
- We also have included our above described automatically operating tabulator mechanism in combination with a power actuated carriage return mechanism of the same general character as 60 that disclosed in the application of Frederick A. Hart, Serial No. 538,725 and have provided automatically operating means for rendering the tabulating mechanism inoperative when the carriage return mechanism is functioning. Such mechanism will now be described, it being understood that only so much of the carriage return mechanism is shown as is necessary to illustrate our present invention in combination therewith.
- 65 Referring more particularly to Fig. 1, it will be seen that the carriage carries a rack 153 which is in constant mesh with a driving pinion 154. Said pinion is carried at the upper end of a shaft 155 and a worm wheel 156 is loosely mounted on the shaft. Said worm wheel is driven by a worm 70 75 156^a that is suitably driven from the motor driven
- pulley 28, shown in Fig. 11. The worm wheel 156 has a clutch section 157 thereon adapted to coact with a second clutch section 158 splined at 158^a on the shaft 155 and provided with a circumferential groove 159 therein. A controlling arm 160 carries a pin 161 that enters the groove 159 and controls the movement of the clutch section 158 into and out of clutching engagement with the clutch section 157. The arm 160 is fixed on the control shaft 143, hereinbefore referred to. From an inspection of Fig. 3 it will be seen that said shaft 143, in addition to the arm 142, is provided with a second crank arm 162 that extends into the control box 147. A hook-like latch 163 coacts with the free end of the arm 162 and holds the parts 15 in the position illustrated in Figs. 1 and 3 with the clutch section 158 released from the clutch section 157. When a return of the carriage is to be effected with the aid of mechanism not shown, but which is similar to that employed in the hereinbefore mentioned Hart application Serial No. 538,725, a hook 164 draws forward the latch 163 and the arm 162 will move upward rocking the shaft 143 and effecting an engagement of the clutch section 158 with the section 157. The effect of this is to return the carriage to the right until the beginning of a line position is reached when the clutch section 158 will again be automatically moved to the Fig. 1 position and released from the clutch section 157.
- 30 It will be understood that when the parts are in the Fig. 2 position and thus conditioned as above described to return the carriage, the shaft 143 (see Fig. 3) will be rocked in the direction of the arrow, lowering the arm 142. This will result 35 in effecting a downward movement of the link 138, and in rocking the shaft 135 to effect an upward movement of the arm 108. This will turn the lever 98 on its pivot 101 and will withdraw the upper end 99 of said lever from cooperative relation with the cam blocks 90 and thus prevent injury to the parts during the rapid return of the carriage under control of the power actuated carriage return mechanism. When the shaft 143 is rocked back to normal position shown in Fig. 1 45 at the conclusion of the return movement of the carriage the control lever 98 will be restored to cooperative relation with the cam blocks 90.
- 40 It has been found desirable to lock the numeral printing keys 165 (see Fig. 7) and also the usual alphabet key levers 166 (see Fig. 13) against actuation during the automatic operation of the tabulator mechanism and during the return of the carriage by its power actuated mechanism.
- 45 With this purpose in view we have provided 50 the following mechanism.
- 55 Referring more particularly to Figs. 1 and 3 it should be borne in mind what has been hereinbefore explained, that when the machine is conditioned to return the carriage by its power driven means, the rock shaft 143 is turned in the direction of the arrow in Fig. 3. The effect of this is to move forward a depending arm 167 fixedly, though adjustably, mounted on the shaft 143. This arm coacts with a laterally projecting stud 60 or roller 168 that is mounted on a crank arm 169 fixedly, though adjustably, secured to a rock shaft 170. This stud 168 is extended to the right of the crank arm 169 as indicated at 168^a. The extension 168^a (see Figs. 1, 2 and 14) enters an 65 elongated slot 171 in an actuating link 172 being normally located at the forward end of said slot, as shown in Fig. 1. The link 172 comprises two lengthwise relatively adjustable sections united by screws 172^a.

Referring to Fig. 13 it will be seen that the forward end portion of the link 172 is detachably pivoted at 173 to a depending arm or lever 174 pivoted at its upper end on a pivot rod 175. The lower end of the arm 174 is detachably pivoted at 176 to a link 177 which in turn is detachably pivoted at 178 to a forwardly extending link 179. By referring to Fig. 7 it will be seen that the link 179 is pivoted at its forward end to a crank arm 180 by which a ball lock for the numeral keys 165 is controlled as disclosed in the application of Hart Serial No. 549,852. Thus the crank arm 180 is fixedly, though adjustably, secured to a rock shaft 181 surrounded by a returning spring 182. Near one end of this shaft is secured a locking arm 183 adapted to enter a slot 184 in a housing 185 that receives a series of locking balls 186 that extend across the machine beneath the series of key levers 187 by which the numeral keys 165 are carried. The housing 185 also is slotted at 188 in register with each key lever 187 to receive and permit it to enter the space between adjacent locking balls. The series of locking balls coact with the end walls of the channel and are so located that there is only sufficient room to receive at one time either a key lever 187 or the locking arm 183. When the locking arm 183 is moved forward between adjacent locking balls the remainder of them are crowded together and against the end walls of the channel and lock all of the key levers 187 against depression or against sufficient movement to bring about an actuation of a numeral type bar and the computing mechanism controlled thereby. In a like manner the balls will be crowded into locking position by the depression of any key lever 187 so that the remainder of said levers are locked against an actuating depression until the first depressed key lever has returned to normal position. Suitable stops (not shown) are provided for limiting the rocking movement of the shaft 181 in opposite directions and the effect of this is to limit the corresponding movements of the links 179 and 172 and the parts controlled thereby whereas such parts are returned to normal position by the spring 182 which returns the rock shaft 181 to normal position.

From the foregoing description it will be understood that when the carriage is being automatically returned by its power driven mechanism, the preliminary rocking of the shaft 143 in the direction of the arrow in Fig. 3 will result in moving the depending arm 167 forward. This in turn will result in moving the links 172 and 179 forward, thereby rocking the shaft 181 and causing the ball lock to prevent an actuation of any of the numeral keys 165.

It is sometimes found to be advantageous to lock the alphabet key levers 166 against operation as well as the numeral keys. When this is found to be desirable, we provide an additional lock which also is controlled by the link 172 and which will now be described.

Referring more particularly to Fig. 13 it will be seen that the link 172 is extended forward of its pivotal connection 173 to form an extension 189 that is bifurcated at 190 where it is received in a slot 191 in a locking frame 192. The bifurcated end 190 straddles the upright plate of said frame 192 and is adapted to engage it on opposite sides thereof. This frame 192 extends from side to side of the machine above the alphabet key levers 166 and is pivoted at the ends thereof to the side plates of the upper frame section 16, as indicated at 193. The locking frame 192 is provided with a rear-

wardly extending locking flange 194 which when the link 172 is shifted rearward from the Fig. 13 position will be moved beneath a series of projections on engaging members 195. One of these engaging members is pivoted to each key lever 166, as indicated at 196, directly beneath the engaging portion of the companion member 195. A contractile spring 197 is connected at one end of each member 195 and at the other end to the companion key lever 166 and tends normally to hold the associated member 195 in effective position. A stop pin 198 is carried by and projects laterally from each key lever 166 through an opening 199 in the companion arresting member 195 and thus limits the motion of said member in both directions around its pivot 196.

This construction is such that a forward movement of the link 172 not only will result in locking the ball lock as previously described, but also will result in moving the flange 194 beneath the 20 engaging hook-like engaging portions of all of the engaging members 195 thereby locking the key levers 166 against an effective depression or one which will cause an actuation of the parts controlled thereby.

If it should happen that a key lever 166 is depressed at the time when the link 172 is moved forward, then the cam edge 200 on the associated engaging member 195 will be beneath the rear edge of the flange 194. When, therefore, the key 30 of said depressed key lever is released and returns to normal position, the upper end portion of the companion arresting member will be cammed rearward by the flange 194 against the force of the associated spring 197. When said 35 cam edge passes the flange 194, the spring 197 will return the engaging member to its normal position shown in Fig. 13 and it will prevent another depression of said key lever as long as the locking frame 192 remains in locking position. 40

In addition to automatically locking the alphabet and numeral keys (either or both) against actuation when the carriage is being returned by its power actuated return mechanism, we prefer to lock such keys against actuation when the automatic tabulator is functioning. To this end we prefer to employ the following mechanism.

Referring more particularly to Fig. 3, it will be seen that a sheet metal yoke-like control member 201 is loosely mounted on the shaft 143 between collars 202 fixedly held on the shaft. This control member has a depending arm 203 that terminates in a contact shoe 204 that coacts with the rear end of the link 172. Said control member 201 also has a rearwardly extending arm 205 provided with a laterally extending ear 206. This ear is pierced to receive loosely therethrough the rod 114 hereinbefore described. A coiled expansion spring 207 surrounds this rod and bears at its lower end against a washer 208 that rests 60 on the ear 206 and at its upper end bears against a collar 209 fixed on the rod 114.

From a consideration of Fig. 2 it will be seen that when the frame 102 is turned to the position shown in this figure under an automatic tabulating operation, the control member 201 will be rocked on the shaft 143 thereby shifting the link 172 forward and effecting a locking of both the numeral and alphabet keys as previously described. Due to the slot 171 in the link 172 this movement of the link is effected independently of the stud 168, 168^a and the parts to which it is connected.

The strength of the spring 207 is such that the above described movement of the control member 75

201 and the parts controlled thereby is brought about without flexing said spring 207, or materially flexing it. However, if the locking balls 186 should be blocked against movement by a depressed numeral key when the rod 114 is actuated as indicated above, then the spring 207 will be flexed and no movement will be transmitted to the parts 201 and the links 172 and 179 until such time as the ball lock is released. When the ball lock is released, the effective force of the spring 207 will turn the member 201 and shift the links 172 and 179 forward thereby causing the locking arm 183 to be shifted to effective position and the locking frame 192 to be moved to locking position in the event that the latter is employed.

It also is desirable to automatically effect a locking of the numeral and alphabet keys when any of the usual denominational tabulator keys 210 (shown in Fig. 19) is actuated. To this end we have provided the following construction.

Referring more particularly to Figs. 1, 3, 14 and 15 it will be seen that the shaft 170 to which the arm 169 is fixedly, though adjustably, secured, also has fixed thereto a depending crank arm 211. This arm coacts with a laterally projecting pin 212 carried by a crank arm 213 fixedly, though adjustably, secured to the rock shaft 127 which carries the crank arms 126 and 128. As previously pointed out, these crank arms are connected respectively to the links 124 and 130, the first of which is controlled by the universal bar 118 and the second of which controls the carriage release mechanism.

From what has been pointed out above it will be understood that when any of the denominational tabulator keys 210 is actuated it results not only in projecting the associated stop 83 to effective position, but also results in rocking the shaft 127 clockwise as the parts appear in Fig. 14, and through the intermediate connections 213, 211, 170 and 169 will move the link 172 forward locking the numeral keys and the alphabet keys as well against actuation.

It is sometimes desirable to have the carriage travel by a single jump to a predetermined point without being arrested at the intermediate columnar positions or fields. In order to attain this result there is provided in the present instance a so-called single-key tabulator mechanism which may be actuated without being interfered with by the automatic tabulator mechanism. This mechanism will now be described.

Referring more particularly to Figs. 1, 16, 17 and 20 it will be seen that the power driven shaft 29 (Fig. 20) on which the cam 30 is mounted also has mounted thereon near its right-hand end a like cam 214 having a second cam 215. These cams, the locking wheel 216, the latch 217, detent 218, trip member 219—220 are like the corresponding parts at the other end of the shaft 29 which are controlled by the automatically operating tabulator mechanism, although the release of the cam 214 is key controlled as will now appear.

Referring more particularly to Figs. 19 and 20 it will be seen that a tabulator skip key 221 is arranged at the right-hand end of the series of tabulator keys and is mounted on a bell crank key lever 222. The mechanism controlled by a depression of this key up to and including the associated stop lever 79 is similar to that disclosed in the said Hart application 634,670 and but a brief description thereof will be given. One arm of this key lever 222 is pivoted at 223 to a push rod or bar 224 provided with an upwardly

extending projection to which one end of a contractile returning spring 225 is connected. The rear end portion of the push rod is supported by a roller 226 and is guided in a slotted guide plate 227. The upper edge of the push bar 224 has a cam 228 that terminates in a dwell 229. A roller 230 bears on the upper edge of the push bar 224 and is carried by a vertically disposed slide 231 which is guided for up and down movement only by suitable guiding means including the plate 227. The upper end of the slide 231 underlies and coacts with an interponent 232 that on the depression of the key 221 will be elevated around its pivot 233 into the path of a bail or universal actuating bar 234 to be actuated thereby when the cam 214 is turned. The pivot 233 connects the associated interponent 232 to the right-hand actuating arm 65b.

The pivoted universal bar or plate 234a is engaged and actuated by a shoulder 231a on the slide 231 during the upward movement of said slide from the Fig. 21 to the Fig. 20 position. This also is true of any of the corresponding slides for the denominational tabulator mechanism. One end of the universal bar 234a coacts with an inwardly extending pin 235 carried by a vertically movable slide 236 that is pivoted at its lower end at 237 to the trip member 219—220. A returning spring 238 is connected to the slide 236 and exerts its force to return the said slide and the parts connected therewith to the normal Fig. 21 position. It will be understood that a bearing roller 239 is carried by and off-set laterally from one of the supporting arms 240 of the actuating bar 234 and that said roller bears against the periphery of the associated cam 214.

On the depression of the tabulator key 221 the corresponding interponent 232 will be elevated into the path of the bar 234. After such movement the trip member 219—220 will be actuated to bring about a partial rotation of the cam 214. The result of this is to actuate the arm 65b and corresponding slide 67a and stop lever 79. However, in this instance the actuation of the stop lever 79 does not result in actuating one of the stops 83 but actuates a special stop 245 that is out of the path of travel of the engaging portions of the stops 83 as will now appear.

The upper end of the right-hand stop lever 79 engages in a slot in a special slide 241, similar to the stops 83 except that it is cut off at the forward end and when projected forward will not extend into the path of the column stops 84. This slide 241 has an upwardly extending projection 242 that projects into a slot 243 in a slide 244. This slide is mounted in the tabulator frame 75 near the top thereof and above the tabulator stops 83 to slide fore and aft of the machine. This slide carries the stop 245 at the forward edge thereof for cooperation with a special column stop 246, the stop 245 when projected being above and out of the path of travel of the engaging portions of the column stops 84. It will be understood therefore that in the event of a depression of the tabulator key 221, the carriage will be arrested by the cooperation of the column stop 246 with the projected stop 245, none of the intervening column stops 84 being effective at this time in the event that the automatic tabulator is at this time rendered inoperative.

We have provided means for automatically rendering the automatic tabulator ineffective or inoperative when the skipping tabulating mechanism controlled by the key 221 is actuated. Such means will now be described.

Projecting into the left-hand end of the slot 243 (see Fig. 18) of the slide 244 is one arm 247 of a bell crank lever (see Fig. 16) pivoted at 248 in the tabulator frame 75. The other arm 111 of this bell crank lever extends forward and overlies the right-hand arm of the control lever 98 and constitutes a stop to limit the pivotal movement thereof under the force of its spring 109, as hereinbefore pointed out. When the slide 244 is moved forward, the lever 247, 111 will be turned clockwise as the parts appear in Fig. 16, thereby lowering the right-hand contact end of said lever 98 out of cooperation with the cams 90, thus rendering the automatic tabulator inoperative.

15 The carriage will, nevertheless, be released at this time due to the operation of the universal bar 118 by the actuated lever 79 and the train of connections 124, 126, 127, 128 and 130 as previously pointed out. Moreover, the alphabet and 20 numeral keys will be locked at this time due to the simultaneous operation of the train of devices 213, 211, 170, 169, 168^a and 172 controlled by the rock shaft 127.

We also have provided means whereby the automatic tabulator will be rendered ineffective or inoperative when the carriage is released with the aid of the usual carriage release key or keys. Such means will now be described.

Referring more particularly to Figs. 16 and 18, 30 it will be seen that one arm 249 of one of the usual carriage release levers underlies one end portion of the feed rack 22. When the associated release key (not shown) is depressed, the arm 249 is elevated thus lifting the feed rack out of engagement with its cooperative feed pinion 26 and freeing the carriage from control of its escape- 35 ment mechanism. A crank arm 250 overlies the feed rack 22 and is secured to a shaft 251 which has a rocking and also a longitudinal movement 40 in bearings in a fixed bracket 252. The inner end portion of this shaft has a rearwardly projecting crank arm 253 secured thereto. This arm normally overlies the right-hand arm of the control lever 98 at the upwardly inclined engaging portion 45 thereof, as shown in Fig. 16. It follows therefore that when the feed rack is lifted by the actuation of the carriage release lever or either of them, the feed rack 22 will be elevated thus turning the shaft 251 and depressing the 50 arm 253 thereby rocking the control lever 98 on its pivot 101, carrying the engaging end of the control lever out of the path of the cams 90 thus rendering the automatic tabulator mechanism inoperative.

55 We have provided means whereby the rocking of the shaft 251 as just described will be rendered ineffective on the control lever 98 during the automatic tabulation, and when the feed rack 22 is lifted by the rack lifting device 132 at such time. 60 Such means will now be described.

Referring more particularly to Figs. 16, 17 and 18 it will be seen that the shaft 251 is surrounded by an expansion spring 254 which at one end abuts the bracket 252 and at its other end bears 65 against the crank arm 250 thus tending to force the shaft 251 to and maintain it at the limit of its longitudinal movement to the right. In this position the crank arm 253 on the shaft will be effective on the control lever 98 when the shaft 70 is rocked as previously described. When, however, the shaft 251 is shifted to the left from its normal position, so that the arm 253 is moved from over the inclined portion of the control lever substantially to the horizontally disposed portion 75 thereof, then a rocking of the arm 253 with the

shaft 251 will be ineffective on the control lever and it will remain in effective position for coaction with the cams 90.

In order to bring about automatically a longitudinal shifting of the shaft 251 to the left we have provided a cam member 255 pivoted at 256 5 on the bracket 252. A cam edge 257 is provided on the member 255 for cooperation with the right-hand end of the hub 258 of the crank arm 253. The member 255 also has an off-set contact 10 face 259 with which an off-set lug 260 on a lever 261 is adapted to engage to turn the cam member 255 from the Fig. 16 to the Fig. 17 position. The result of this is to shift the shaft 251 to the left with the result hereinbefore indicated, and to 15 hold the parts in this condition as long as the cam member is held in its actuated position.

The lever 261 is pivoted at 262 to the bracket 252 and the right-hand arm of said lever overlies the rack lifting device 132. As the latter is 20 actuated to lift the rack 22 it also will actuate the lever 261 moving it from the Fig. 16 to the Fig. 17 position with the result that the shaft 251 is shifted to the left and a rocking of the arm 253 at this time is ineffective on the control lever 25 98. When the denominational tabulator is to be used, the manually controlled lever 145 is shifted to and retained in the locking notch 152, thereby rendering the automatically operating tabulator 30 inoperative and free from interference with the denominational tabulator.

When we refer herein and in the accompanying claims to "manually controlled" denominational and column skipping tabulator mechanisms, etc., it will be understood that such term is employed 35 to differentiate from an automatically operating tabulator mechanism and is applicable alike to such denominational and column skipping tabulator mechanisms, etc., whether they be power actuated as disclosed herein or are manually actuated in their entirety.

It is thought that in view of the foregoing description it will be unnecessary to describe more fully the operation of the machine under varying 45 conditions of use. However, it will be seen that by our invention we have provided—

(a) A power actuated automatically operating tabulator mechanism which is comparatively simple in construction and efficient in use;

(b) Manually controlled means comprising the parts 145, 151, etc., that operate at the will of the operator for rendering and maintaining indefinitely said automatically operating means inoperative;

(c) Means for automatically locking printing 55 keys against actuation when said automatically operating mechanism is actuated;

(d) Column jumping means comprising the parts 221, 245, 246, etc., together with means for automatically rendering the automatic tabulator mechanism inoperative when said column jumping means are actuated;

(e) Means for automatically locking printing 60 keys against actuation when the column jumping means are actuated;

(f) Denominational tabulator mechanism together with means for rendering said automatically operating tabulator ineffective when the denominational tabulator mechanism is actuated;

(g) Means for automatically locking printing 70 keys against actuation when said denominational tabulator mechanism is actuated;

(h) Means for rendering said automatically operating tabulator mechanism inoperative when 75

the carriage is released by the usual carriage release key or keys;

5 (i) Means for rendering said automatically operating tabulator mechanism inoperative when the carriage is being returned by its power actuated carriage return mechanism;

(j) Means whereby printing keys will be locked against actuation when said carriage return mechanism is actuated;

10 (k) Means whereby the above mentioned mechanisms may be incorporated in a machine having two relatively movable frame sections and which will not interfere with such relative movement of the sections;

15 (l) A construction whereby the foregoing features may be readily embodied in existing machines without materially modifying the existing structural features thereof.

(m) A construction of such a character that 20 during the return of the carriage by hand or otherwise the automatically operating tabulator mechanism will not function.

25 While we have described one form of construction embodying our invention in detail, it should be understood that various changes may be made therein, and that parts thereof may be employed without the inclusion of other parts, without departing from our invention as it is defined in the accompanying claims.

30 We believe that we are the first to provide power actuated, automatically operating, tabulator mechanism and have claimed such mechanism broadly.

35 What we claim as new and desire to secure by Letters Patent is:

1. In an automatic power actuated tabulator mechanism for typewriting and like machines, the combination of a carriage, a tabulator stop, power controlled means for projecting said tabulator stop to effective position and for releasing the carriage, and controlling means automatically operative at a predetermined point in the travel of the carriage for rendering said power controlled means effective to project said tabulator 45 stop and for releasing the carriage.

2. In an automatic power actuated tabulator mechanism for typewriting and like machines, the combination of a carriage, a tabulator stop, power controlled means for projecting said tabulator stop to effective position and for releasing the carriage, and controlling means automatically operative at a predetermined point in the travel of the carriage for rendering said power controlled means effective to project said tabulator stop and for releasing the carriage, said controlling means including adjustable means by which the point or points in the travel of the carriage where the tabulator stop is projected and the carriage released may be predetermined.

60 3. In an automatic power actuated tabulator mechanism for typewriting and like machines, the combination of a carriage, a tabulator stop, power controlled means for projecting said tabulator stop to effective position and for releasing the carriage, and controlling means automatically operative at a predetermined point in the travel of the carriage for rendering said power controlled means effective to project said tabulator stop and for releasing the carriage, said controlling means including means whereby they are rendered ineffective to function during the return movement of the carriage.

4. The combination of a carriage, a contact device carried thereby, a tabulator stop, carriage 75 releasing means, power actuated means for pro-

jecting said tabulator stop and for operating said carriage releasing means, and means controlled by said contact device for automatically rendering the power controlled means effective to project the tabulator stop and for actuating said carriage releasing means.

5 5. The combination of a carriage, a cam carried thereby, a tabulator stop, carriage releasing means, power actuated means for projecting said tabulator stops and for operating said carriage releasing means, and means controlled by said cam for automatically rendering the power controlled means effective to project the tabulator stop and for actuating said carriage releasing means.

10 6. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, key locking 20 means, and automatically operating means for rendering said key locking means effective when the tabulator stop is actuated and the carriage is released.

15 7. The combination of a carriage, a contact carried thereby, finger keys, a lock for said finger keys, a tabulator stop, carriage releasing means, power actuated means for projecting said tabulator stop and for operating said carriage releasing means, means controlled by said contact for rendering the power controlled means effective to project the tabulator stop and release the carriage, and means also controlled by said contact for actuating said lock to lock the finger 30 keys.

25 8. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, and manually controlled means settable at will for rendering said automatic tabulator mechanism inoperative.

35 9. The combination of a carriage, a cam carried thereby and having a dwell thereon, a tabulator stop, carriage releasing means, power actuated means for projecting said tabulator stop and operating said carriage releasing means, and means controlled by said cam for rendering the power controlled means effective to project the tabulator stop and for actuating said carriage releasing means, the construction and arrangement of the parts being such that the length of the dwell on the cam determines the length of time that the tabulator stop remains projected and the carriage released.

40 10. The combination of a carriage, power actuated carriage return mechanism, power actuated automatic tabulator mechanism operative automatically at a predetermined point in the advance of the carriage, and automatically operating 45 means for rendering said tabulator mechanism ineffective when the carriage return mechanism is operative.

11. The combination of a carriage, power actuated carriage return mechanism, power actu-

ated automatic tabulator mechanism operative automatically at a predetermined point in the advance of the carriage and comprising a contact on the carriage and controlling means with which said contact coacts, and means controlled by said carriage return mechanism for rendering said contact ineffective on said controlling means in the return movement of the carriage.

12. The combination of a carriage, carriage releasing means, a tabulator stop, a power actuated cam for actuating said tabulator stop and releasing means, and controlling means for automatically rendering said cam operative at a predetermined point in the advance of the carriage.

13. The combination of a carriage, carriage releasing means, a tabulator stop, a power actuated cam for actuating said tabulator stop and releasing means, and controlling means for automatically rendering said cam operative at a predetermined point in the advance of the carriage, said controlling means including means by which they are rendered ineffective during the return movement of the carriage.

14. The combination of a carriage, carriage releasing means, a tabulator stop, a power actuated cam for actuating said tabulator stop and releasing means, controlling means for automatically rendering said cam operative at a predetermined point in the advance of the carriage, power actuated carriage return mechanism, and means controlled thereby for rendering said controlling means ineffective.

15. The combination of a carriage, carriage releasing means, a tabulator stop, a continuously operating power actuated driving shaft, a cam actuated thereby, connecting means for operatively connecting said cam to said shaft, said tabulator stop and carriage releasing means being controlled by said cam, and controlling means actuated at a predetermined point in the advance of the carriage and operative on said connecting means to operatively connect said cam to its power actuated driving shaft.

16. The combination of a carriage, carriage releasing means, a tabulator stop, a continuously operating power actuated driving shaft, a cam actuated thereby, connecting means for operatively connecting said cam to said shaft, said tabulator stop and carriage releasing means being controlled by said cam, controlling means actuated at a predetermined point in the advance of the carriage and operative on said connecting means to operatively connect said cam to its power actuated driving shaft, and means operable at will for maintaining said controlling means inoperative.

17. The combination of a carriage, carriage releasing means, a tabulator stop, a continuously operating power actuated driving shaft, a cam actuated thereby, connecting means for operatively connecting said cam to said shaft, said tabulator stop and carriage releasing means being controlled by said cam, and controlling means actuated at a predetermined point in the advance of the carriage and operative on said connecting means to operatively connect said cam to its power actuated driving shaft, said controlling means including means by which they are rendered ineffective during the return movement of the carriage.

18. The combination of a carriage, carriage releasing means, a tabulator stop, a continuously operating power actuated driving shaft, a cam actuated thereby, connecting means for operatively connecting said cam to said shaft, said

tabulator stop and carriage releasing means being controlled by said cam, controlling means actuated at a predetermined point in the advance of the carriage and operative on said connecting means to operatively connect said cam to its power actuated driving shaft, printing keys, locking means for locking said keys against actuation, and automatically operating means for actuating said locking means to lock the keys when said controlling means are actuated.

19. In an automatic power actuated tabulator mechanism for typewriting and like machines, the combination of a carriage, a tabulator stop, power controlled means for projecting said tabulator stop to effective position and for releasing the carriage, and controlling means automatically operative at a predetermined point in the travel of the carriage for rendering said power controlled means effective to project said tabulator stop and for releasing the carriage, said controlling means comprising a pivoted actuating frame, and means on the carriage for effecting a pivotal movement of said frame at a predetermined point in the advance of the carriage.

20. In an automatic power actuated tabulator mechanism for typewriting and like machines, the combination of a carriage, a tabulator stop, power controlled means for projecting said tabulator stop to effective position and for releasing the carriage, and controlling means automatically operative at a predetermined point in the travel of the carriage for rendering said power controlled means effective to project said tabulator stop and for releasing the carriage, said controlling means comprising a pivoted frame, a lever pivoted for independent movement on said frame, and a contact on the carriage so constructed and arranged as to coact with said lever at a predetermined point in the advance of the carriage to effect a pivotal movement of the frame and to effect an independent movement of the lever on said frame during the return movement of the carriage.

21. In an automatic power actuated tabulator mechanism for typewriting and like machines, the combination of a carriage, a tabulator stop, power controlled means for projecting said tabulator stop to effective position and for releasing the carriage, and controlling means automatically operative at a predetermined point in the travel of the carriage for rendering said power controlled means effective to project said tabulator stop and for releasing the carriage, said controlling means comprising a pivoted frame, a lever pivoted for independent movement on said frame, a contact on the carriage so constructed and arranged as to coact with said lever at a predetermined point in the advance of the carriage to effect a pivotal movement of the frame and to effect an independent movement of the lever on said frame during the return movement of the carriage, and manually controlled means settable at will for maintaining said lever out of cooperative relation with said contact and for thereby rendering the automatic tabulator mechanism inoperative.

22. The combination of a carriage, power actuated carriage return mechanism, power actuated automatic tabulator mechanism operative automatically at a predetermined point in the advance of the carriage, and automatically operating means for rendering said tabulator mechanism ineffective when the carriage return mechanism is operative, the construction comprising a pivoted frame, a lever pivoted for independent

movement on said frame, a contact on the carriage so constructed and arranged as to coat with said lever at a predetermined point in the advance of the carriage to effect a pivotal movement of said frame and for thereby rendering the power actuated tabulator mechanism operative, and means controlled by said carriage return mechanism for automatically effecting an independent movement of said lever to move it out of cooperative relation with said contact and for thereby rendering the automatic tabulator mechanism inoperative.

23. The combination of a carriage, carriage releasing means, a tabulator stop, a continuously operating power actuated driving shaft, a cam actuated thereby, connecting means for operatively connecting said cam to said shaft, said tabulator stop and carriage releasing means being controlled by said cam, and controlling means actuated at a predetermined point in the advance of the carriage and operative on said connecting means to operatively connect said cam to its power actuated driving shaft, said controlling means including a controlling cam with a dwell thereon, the construction and arrangement of the parts being such that the length of the dwell on said controlling cam determines the length of time that said first mentioned cam shall be maintained in effective position.

30 24. The combination of a carriage, a tabulator stop, carriage releasing means, a power driven rotative cam by which said stop and releasing means are controlled, and controlling means automatically actuated at a predetermined point in the travel of the carriage to connect said cam to its power driving means during a portion only of the cycle of said cam to move it to actuated position and afterwards reconnect it to its power driving means to complete the cycle of the cam and return it to normal position, said controlling means comprising a controlling cam movable with the carriage and having a dwell thereon, the construction and arrangement of the parts being such that the length of the dwell on the controlling cam determines the length of time that the power driven cam remains in its actuated position.

25. The combination of a carriage, a tabulator stop, carriage releasing means, power actuated means for controlling the movements of said tabulator stop and releasing means to and from effective position, and controlling means automatically actuated at predetermined points in the travel of the carriage for controlling the movements of the tabulator stop and carriage releasing means to and from effective position, said controlling means including means for predetermining the extent of time that said stop and releasing means shall be retained in the actuated position at each tabulating operation.

60 26. The combination of a carriage, a tabulator stop, carriage releasing means, power actuated means for controlling the movements of said tabulator stop and releasing means to and from effective position, and controlling means automatically actuated at predetermined points in the travel of the carriage for controlling the movements of the tabulator stop and carriage releasing means to and from effective position, said controlling means including a plurality of contact devices of different lengths, and means controlled thereby for maintaining the stop and releasing means in actuated position different lengths of time depending on the length of the particular contact device which is in use.

27. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, a machine frame comprising two relatively movable sections, some of the elements of said automatic power actuated tabulator mechanism being carried by one of said sections and other elements thereof carried by the other of said frame sections without interfering with the relative movement of said frame sections, the construction and arrangement of the parts being such that cooperative elements on the two frame sections are brought into cooperative relation when the sections are brought together.

28. The combination of a machine frame comprising two relatively movable sections, automatically operating tabulator mechanism including elements thereof carried by one of said relatively movable frame sections and other elements thereof carried by the other frame section, the construction and arrangement of the parts being such that cooperative tabulator elements on the two frame sections will be brought into cooperative relation when the frame sections are brought together in the event that such elements are in their normal position relative to the frame section which carries them, a support for certain of said tabulator elements and which is movably mounted on one of the frame sections, and spring means tending to maintain said support in fixed relation to the frame section which carries it, whereby in the event that one of the cooperative tabulator elements is not in normal position 40 when the frame sections are brought together said support will be moved against the force of its spring means and no injury to the structure will result.

29. The combination of a machine frame comprising two relatively movable sections, automatically operating tabulator mechanism including controlling means therefor automatically operated at a predetermined point in the travel of the carriage, elements of said controlling means being carried by one of said frame sections and other cooperative elements of the controlling means being carried by the other frame section, the construction and arrangement of the parts being such that said cooperative elements are moved out of cooperative relation without interfering with the separation of the frame sections and are brought into cooperative relation when the frame sections are brought together.

30. The combination of automatic tabulator mechanism, manually controlled column skipping tabulator mechanism, each of said tabulator mechanisms being actuated independently of the other to effect an arrest of the carriage in a columnar position and automatically operating means for rendering said automatic tabulator mechanism inoperative when said column skipping mechanism is actuated.

31. The combination of a carriage having a step-by-step letter feed movement, power actuated tabulator mechanism that is automatically actuated when the carriage reaches a predetermined point in its travel, a separate and distinct manually controlled column skipping tabulator mechanism, and automatically operating means

for rendering said automatic tabulator mechanism inoperative when said column skipping mechanism is actuated.

32. The combination of a carriage, automatic tabulator mechanism comprising a control member, and actuating means that operate thereon at a predetermined point or at predetermined points in the travel of the carriage, column skip tabulator mechanism operable independently of said automatic tabulator mechanism to effect an arrest of the carriage in a columnar position, and means controlled by said column skip tabulator mechanism for rendering said actuating means inoperative on said control member.

33. The combination of a carriage, automatic tabulator mechanism comprising a control lever, one or more contact devices that cooperate with and actuate said control lever at a predetermined point or points in the travel of the carriage, column skip tabulator mechanism, and means controlled thereby for shifting said control lever out of cooperative relation with said contact device or devices.

34. The combination of a carriage, power actuated automatic tabulator mechanism comprising a control member for rendering the power means effective to actuate said tabulator mechanism, manually controlled tabulator mechanism, and means controlled thereby for automatically rendering said automatic tabulator mechanism inoperative.

35. The combination of a carriage having a step-by-step letter feed movement, power actuated tabulator mechanism that is automatically actuated when the carriage reaches a predetermined point in its travel, separate and distinct manually controlled tabulator mechanism, and means controlled thereby for rendering said automatically actuated tabulator mechanism inoperative.

36. The combination of a carriage, power actuated automatically operating tabulator mechanism comprising a control member for rendering the power means effective to actuate said automatically operating tabulator mechanism, manually controlled tabulator mechanism, and means controlled thereby and operative on said control member for automatically rendering said automatically operating tabulator mechanism inoperative.

37. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, manually controlled tabulator mechanism, and means controlled thereby for rendering said controlling means inoperative to render said power controlled means effective.

38. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, manually controlled column skip tabulator mechanism, and

means controlled thereby for rendering said controlling means inoperative to render said power controlled means effective.

39. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, said controlling means including adjustable means by which the point or points in the travel of the carriage where the tabulator stop is projected and the carriage released may be predetermined, manually controlled tabulator mechanism, and means controlled thereby for rendering said controlling means inoperative to render said power controlled means effective.

40. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, power actuated carriage return mechanism, manually controlled tabulator mechanism, and means controlled by said carriage return mechanism and also by said manually controlled tabulator mechanism for rendering said controlling means inoperative to render the power controlled means effective.

41. The combination of a carriage, power actuated automatically operating tabulator mechanism, manually controlled tabulator mechanism, means controlled thereby for rendering said automatically operating tabulator mechanism inoperative, printing keys, locking means therefor, and means for automatically actuating said locking means to lock said keys when said automatically operating tabulator mechanism is actuated and also when said manually controlled tabulator mechanism is actuated.

42. The combination of a carriage, power actuated automatically operating tabulator mechanism, manually controlled tabulator mechanism, means controlled thereby for rendering said automatically operating tabulator mechanism inoperative, power actuated carriage return mechanism, printing keys, locking means for locking said printing keys against actuation, and means for automatically actuating said locking means when the power actuated carriage return mechanism is actuated and also when the automatically operating or manually controlled tabulator mechanisms are actuated.

43. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, said controlling means comprising a pivoted frame, a lever pivoted for independent movement on said frame, and a contact on the carriage so con-

structed and arranged as to coact with said lever at a predetermined point in the advance of the carriage to effect a pivotal movement of the frame, manually controlled tabulator mechanism, 5 and means controlled thereby for effecting an independent pivotal movement of said lever out of cooperative relation with said contact, whereby the automatically operating tabulator mechanism is rendered ineffective when the manually 10 controlled tabulator mechanism is actuated.

44. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator 20 stop and for releasing the carriage, said controlling means comprising a pivoted frame, a lever pivoted for independent movement on said frame, and a contact on the carriage so constructed and arranged as to coact with said lever at a predetermined point in the advance of the carriage to effect a pivotal movement of the frame, power actuated carriage return mechanism, and means controlled thereby for effecting an independent pivotal movement of said lever out of cooperative 25 relation with said contact, whereby the automatically operating tabulator mechanism is rendered inoperative when the carriage return mechanism is actuated.

45. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel of the carriage for rendering said power controlled means effective to project said tabulator stop and for releasing the carriage, said controlling means comprising a pivoted frame, a lever pivoted for independent movement on said frame, and a contact on the carriage so constructed and arranged as to coact with said lever at a predetermined point in the advance of the carriage to effect a pivotal movement of the frame, a 50 manually controlled member shiftable into and out of effective position, means for holding said member in either of said positions, and means controlled by said member for effecting an independent movement of said lever out of cooperative relation with said contact, whereby the automatically operating tabulator mechanism may be rendered and maintained inoperative.

46. In an automatic power actuated tabulator mechanism for typewriting and like machines, the combination of a carriage, a tabulator stop, power controlled means for projecting said tabulator stop to effective position and for releasing the carriage, controlling means automatically operative at a predetermined point in the travel 65 of the carriage for rendering said power controlled means effective to project said tabulator stop and for releasing the carriage, two rela-

tively movable frame sections, some of the parts of the aforementioned power controlled tabulator mechanism being included in one frame section and parts thereof included in the other frame section, the construction and arrangement of 5 the parts being such that coacting parts on the two frame sections are brought into cooperative relation when the frame sections are brought together.

47. The combination of a frame comprising 10 two relatively movable frame sections, automatically operating tabulating mechanism having parts thereof carried by one of said frame sections and parts thereof carried by the other of said frame sections, the construction and arrangement of 15 the parts being such that cooperative parts of said tabulating mechanism are brought into cooperative relation when the frame sections are brought together.

48. The combination of column stops that 20 have contact portions which travel in one path, a column-jumping column stop that has a contact portion that travels in another path, automatically operating tabulator mechanism including a stop that is automatically projected 25 into the path of said first mentioned column stops only, a key controlled projectable column-jumping stop that coacts only with said column-jumping column stop, and automatically operating means for rendering said automatically operating tabulator mechanism inoperative when the column jumping mechanism is actuated.

49. The combination of a carriage, column stops on the carriage that have contact portions which travel in one path, a column-jumping column stop on the carriage that has a contact portion that travels in another path, automatically operating tabulator mechanism including a power actuated stop that is automatically projected into the path of said first mentioned column stops only, a key controlled power actuated projectable column-jumping stop that coacts only with said column-jumping column stop, and automatically operating means for rendering said automatically operating tabulator mechanism inoperative when the column-jumping mechanism is actuated.

50. The combination of column-jumping tabulator mechanism, denominational tabulator mechanism, power actuated automatically operating tabulator mechanism, and means whereby any of said tabulator mechanisms may be operated without interference by the others, said means including means for rendering the power actuated automatically operating tabulator 50 mechanism inoperative when either the column jumping or the denominational tabulator mechanism is actuated.

51. The combination of power actuated column-jumping tabulator mechanism, power actuated denominational tabulator mechanism, automatically operating power actuated tabulator mechanism, and means whereby any of said power actuated tabulator mechanisms may be operated without interference by the others.

ELBERT S. DODGE.
